9 by means of interrupted seams 10 and 11 in such a manner that a casing or channel 12 is formed through which a coil 14 may extend in order to keep the casing or channel always open. The coil may be of any desired shape or material. I prefer to make the coil of light, resilient material, for instance of horse hair, and to make it of triangular profile as shown in Figs. 6 and 7, or of oval profile as shown in Fig. 12, or round (not shown). The coil will not only keep the casing or channel 12 open, but it will also keep the openings 8, at the interruptions of the main seam, and the openings 16 and 17, at the interruptions of the seams 10 and 11, open so that always a sufficient circulation of air is assured.

A similar seam system as shown in Figs. 5 to 7 inclusive is the one illustrated in Figs. 8 to 10 inclusive, where it will be seen that the pieces 1 and 2 are also connected to each other by an interrupted main seam 7 leaving openings 8, and the outer edges 5 and 6 of the pieces 1 and 2 are connected to a strip 9 by interrupted seams 10 and 11 so that air can circulate through the openings 8, which are covered by the strip 9, and through the openings which occur at the interruptions of the seams 10 and 11. The strip 9 may be at the outer or inner side of the garment; particularly in the case of uniforms I prefer to cover the interrupted seams by outside strips.

If wider openings are desired, the seam system illustrated in Figs. 11 to 14 inclusive may be used; in this case the pieces 1 and 2 are also connected to each other by an interrupted main seam 7, but at the interruptions of this seam 7 there are apertures 19, and in alignment with these apertures 19 there are recesses 20 at both sides of the strip 9. I prefer to use for this system a coil 21 of oval profile, as shown in Fig. 12.

The system shown in Figs. 11 to 14 inclusive can also be used if a row of apertures 19 is in one single piece of cloth and if these apertures should be covered at the inner or outer side by a strip 9 so as to form an always open air channel 12. This use of the system of Figs. 11 to 14 is so obvious that it is not necessary to show it in the drawings.

The coil 21 (and/or 14) can be held in place by means of a hook 22 and an eye, as shown the top of Figs. 11, 13, and 14.

In connection with the various interrupted seams and apertures previously referred to, I prefer to use also inverted box plaits; one example of which is shown in Figs. 15 to 17 inclusive. To provide for circulation of air through said box plaits, I prefer to provide one or two rows of apertures 27 in the rear part 28 of the

inverted box braid and to keep the inverted box braid in shape by means of interrupted seams 29 with openings 30 at the interruptions of said seams 29. In this case the air can pass from the openings 27 through the openings 30 to the body, and the openings 27 are completely invisible, whereas the openings 30 are covered at the inner side by the part 28.

The various systems described above can be used, for instance, on trousers as shown in the diagrams Figs. 18 and 19 or on shirts and the like. The seam system of Figs. 1 to 4 inclusive of Figs. 8 to 10 inclusive may be used for the inner trousers legs seams 32 or for shirt seams

15 and the like; the seam system of Figs. 5 to 7 inclusive or of Figs. 8 to 10 inclusive or of Figs. 11 to 17 inclusive may be used for outer trousers legs seams 43; the seam systems of Figs. 5 to 7 or of Figs. 11 to 14 inclusive may be used—in connection with small coils—for the trousers patch seams 45; the seam system of Figs. 8 to 10 inclusive may be used for the trousers rear part 47.

Although the application of my seam systems and apertures is shown only in the example of a pair of trousers, it will be obvious that these seam systems and apertures can also be used for any other types of garments, apparels, coats, and the like. I prefer to make the apertures and openings at the interruptions of seams larger and to 30 place them at smaller distances from each other at parts of the garments which are adjacent to strongly perspiring parts of the body than at parts of the garments which are adjacent to less perspiring parts of the body.

35 Further modifications will be apparent to those skilled in the art and it is desired, therefore, that my invention be limited only by the prior art and the scope of the appended claim.

Having thus described my invention, what I 40 claim and desire to secure by Letters Patent in the United States is:

A seam for ventilating a garment between adjoining garment sections; the garment sections being joined together by an interrupted seam, 45 the interrupted parts forming openings through the garment, a strip member positioned over the seam and the interrupted parts, the strip member having each of its edges secured to the respective garment section by an interrupted seam, 50 means for maintaining a spaced relation between the garment sections and said strip, said means being substantially coextensive with the first mentioned interrupted seam and positioned between the garment section and strip whereby the 55 space thus formed permits circulation of air through the interruptions between garment sections, and those securing the edges of the strip.

ANTHONY BARONE.
